(57) **CLAIM**

The ornamental design for a sink faucet mat, as shown and described.

DESCRIPTION

FIG. 1 is a front perspective view of a sink faucet mat in accordance with the new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines depict portions of the sink faucet mat that form no part of the claimed design.
